MANUFACTURE OF SOAP-THICKENED COMPOSITIONS AND APPARATUS THEREFOR

Charles Ray Hetherington, Bronxville, N. Y., assignor to California Research Corporation, San Francisco, Calif., a corporation of Delaware

Application November 12, 1946, Serial No. 709,319

6 Claims. (Cl. 252—32)

1

This invention relates to improvements in methods of manufacturing soap-thickened compositions, such as greases, the new products so obtained, and to apparatus for use in connection therewith.

More particularly, the invention pertains to a continuous process of manufacturing lubricating greases involving the efficient dispersing of pre-formed soap stock in recycled finished grease to form an intermediate component, and mutually dispersing oil and the intermediate component to form finished product grease and finished recycle grease.

Though a large percentage of processes in the petroleum industry today are continuous and largely automatic, greases continue to be manufactured largely by batch methods. Batch methods of grease manufacture have numerous deficiencies, among which are the following: (1) an unnecessarily large number of large kettles and blending tanks are required; (2) the amount of floor space per volume of product is high; (3) quality of product is largely dependent on varying skill of the grease operator; (4) because product must be made in large batches, it is substantially impossible to maintain the necessary uniform conditions of temperature and mixture throughout the batch, with the result that it is difficult to obtain uniformity of product; (5) because of inherent poor mixing when handling large batches of material, maximum utilization of the soap stock is not obtained, with the result that more soap stock is required to produce a given penetration grease and more of the expensive soap stock is required.

One object of the present invention is to overcome the disadvantages of the batch methods. According to the herein-described invention, the costs of production are decreased, the grease is not only improved in quality but is uniform. The amount of equipment employed is greatly reduced and the quality of the grease rendered substantially independent of the skill of the operator. In addition, a further saving is obtained because my process permits a reduction in the amount of soap required, soap being the most expensive ingredient of the grease. Furthermore, according to the present invention, light greases containing a comparatively low percentage of soap may be efficiently made in a continuous manner.

My invention may be understood from the following description which has reference to Figure 1 wherein my invention is diagrammatically illustrated. Preformed soap stock continuously metered from soap stock kettles A and B by variable

2

drive metering pump 10 flows through line 12. Mineral oil is continuously drawn into the system from mineral oil storage tanks C and D by variable drive metering pump 13 through meter 14.

The soap stock passes from line 12 through heater 15 for temperature control to the first stage mixing machine 16 wherein it is violently mixed with recycled finished grease supplied by pump 17 through line 18. The material effluent through line 19 from first stage mixer 16 is the intermediate component. It is a dispersion of soap stock and finished grease, the finished grease containing in itself, even prior to admixture with the soap stock, the amount of soap desired in the finished product. The intermediate component effluent from the first stage mixing machine 16 flows continuously through line 19 to the second stage mixing machine 20 wherein it is continuously admixed with proportioned quantities of heated mineral oil stock supplied at controlled temperatures by metering pump 13 through line 21 and heater 22. Material continuously effluent through line 23 from the second stage mixing machine 20 is finished grease. This finished grease flows continuously through line 23, through recycle pump 17 to a junction 24 where finished, recycle grease splits continuously to line 18, and finished, product grease flows continuously through line 26 through a strainer 27 and back pressure controller 28 to product storage 29. The proportion of the finished grease which is to be recycled to the first stage mixing machine 16 through line 18 may be controlled by by-passing finished grease around recycle pump 17 through a by-pass 30 and valve 31.

First stage mixing machine 16 and second stage mixing machine 20 may be any of the numerous high speed mixing machines or dispersers available on the market for dispersing or mixing of this character. One type commonly used is known as the Lancaster disperser. Centrifugal pumps, colloid mills, disc mills, screw pumps and similar equipment, capable of providing intimate mixture and fine dispersion of heavy materials, may be employed as the mixing devices. Usually such equipment obtains its dispersing action by the shearing action of rapidly moving parts and by the use of directing vanes and baffles. A common feature of all such devices, as applied to my process, is their ability to effect an intimate dispersion of the soap stock and recycled finished grease at one stage and the intermediate component and the mineral oil in another stage in

a very short period of time, usually about 10 to 15 seconds.

The above description of my invention is illustrative only and covers only one embodiment of the invention of the appended claims. Obviously the number of stages employed and the circulation of the various components to the employed stages may be widely varied within the scope of the appended claims. For instance, referring to Figure I, it is not necessary that the grease which is recycled to first stage disperser 16 be the finished grease, part of which is passed to produce storage 29. On the contrary, by varying the number of dispersing stages the grease structure continuously circulated back to the first stage disperser may be any intermediate grease structure continuously formed in said continuous process.

It will be noted that the herein-described process may be operated on a fully continuous and automatic basis. Having once made appropriate control settings for temperature and rate of flow of the incoming soap stock and mineral oil stock, the rate of recycling of the finished grease, and having made appropriate settings on metering pumps 10 and 13, heaters 15 and 22 and finished grease by-pass valve 31, the process is continuous and fully automatic. As such, it is independent of the varying skill of the particular operator and the finished grease is uniform in nature. Obviously apparatus for the practice of my process may be equipped with appropriate control mechanisms, valves and the like, so that the process can be operated on a nonautomatic basis, if desired.

I do not, of course, claim to be the first to have disclosed a continuous process of manufacturing soap-thickened compositions. Among the United States patents describing continuous grease-making processes are Nos. 1,912,001; 2,084,974; 2,318,668; 2,332,202; 2,365,037; 2,374,913; 2,383,906; 2,394,567. My process and apparatus, however, are novel and possess outstanding advantages over the processes and apparatus disclosed in the prior art.

One process for continuous manufacture of greases provides for continuously passing proportioned and heated amounts of soap stock and soap-free oil stock to a high speed mixer wherein the grease structure is formed by means of the shearing action of rapidly moving parts, as in the device known in the industry as a Lancaster disperser. One disadvantage of such process is especially pronounced in the manufacture of light greases, i. e., greases containing 10% or less of soap. In such manufacture control for product consistency has been difficult to obtain, in part because there is not obtained an effective mutual dispersion of the soap and oil. Such incomplete dispersion of the soap and the mineral oil results in a finished grease which is unstable and which tends to bleed upon standing. The incomplete dispersion of the soap stock in the oil and the consequent tendency of the finished grease to bleed where the dispersion is accomplished by high speed mixing of soap stock and oil is believed to be caused, especially when the percentage of soap stock is comparatively low, by the wide disparity between the physical properties of the soap stock and of the oil. In my process, in the soap dispersing step, the materials are of substantially more similar physical properties and the mutual dispersion of the soap and the other components is intimate and complete.

In Figure I, I have shown a purely diagrammatic exemplification of my process. Reference is now made to Figure II wherein I have shown a longitudinal sectional view of a preferred apparatus for carrying out the mixing and circulating phases of my process. The apparatus of Figure II per se is described and claimed in a copending joint application in the name of the herein inventor and Ekdred E. Edwards, which application was filed November 12, 1946, and bears Serial No. 709,290.

In Figure II, reference numeral 40 designates generally a plate or other suitable type of end member, provided with a central shaft aperture and stuffing box 41. An opposite end member 42 is spaced from member 40 by means of a cylindrical housing or shell 43, the whole assembly being fastened together with through bolts 44, equally spaced around the periphery of shell 43. A shaft 47 adapted to be driven by a prime mover (not shown) extends through stuffing box 41 and is received in a central bearing 48 in end member 42. Bearing 48 is provided with a plurality of openings 49 adapted to communicate with a central port 50 in housing 42 for the purpose of admitting soap stock, represented by dotted arrows, substantially uniformly around that end of shaft 47 which is received in bearing 48. Mounted on shaft 47, in this example, are three impellers, respectively designated 51, 52 and 53, of the type generally used in centrifugal pumps. These are spaced along shaft 47 by sleeves 54 and 55 and are secured to the shaft by the customary keys (not shown) and a threaded nut 56, adjacent the outboard or bearing end of shaft 47.

Within the housing shell 43 are provided diffusion vane assemblies 57, 58 and 59 similar to those utilized in turbine type centrifugal pumps. Two inlets 60 and 61 are provided in the end member 40 to communicate with an inlet eye of mixing impeller 51. To facilitate this communication, a first diaphragm 62 having a central aperture is positioned within the housing shell 43 adjacent to but spaced from the inner face of end member 40 and the inlet eye of impeller 51. A second diaphragm 63 is positioned on the opposite side of mixing impeller 51 from diaphragm 62 and is provided with apertures 64 near its periphery so that a portion of the fluids or semi-fluids passing outwardly from impeller 51 into diffusion vanes 57 will be redirected inwardly toward shaft 47 to pass through a central aperture 65 in third diaphragm 66, from which the fluids or semi-fluids will be admitted to the inlet or eye of a pumping impeller 52, which is the center impeller of the three in this example.

Desirably, a portion of the fluids or semi-fluids passing through impeller 51 into diffusion vanes 57 recirculate as shown by the arrows to reenter the inlets of that impeller and insure maximum turbulence and mixing.

A fourth diaphragm 67 is positioned on the opposite side of pumping impeller 52 from diaphragm 66 and, similar to diaphragm 63, is provided around its periphery with apertures 68 to cooperate with a fifth diaphragm 69 to redirect at least a portion of the fluids or semi-fluids passing outwardly from impeller 52 through the space between diaphragms 67 and 69 to a central aperture 70 in the latter diaphragm which acts finally to direct the fluids or semi-fluids into an inlet or eye of the third or mixing impeller 53. The clearance or spacing between diaphragms 66 and

67 and impeller 52 is as close as practicable, so that efficient pumping action will be obtained from this impeller.

As pointed out above, fluids or semi-fluids, in this example soap stock represented by dotted arrows, admitted through port 58 enter the opposite eye of mixing impeller 53 from that just described so that mixing of the respective fluids or semi-fluids will take place within the last-named impeller and its corresponding diffuser 59. It will be noted from the arrows on the drawing that recirculation from the periphery of impeller 53 inwardly to the eyes thereof is facilitated by the spacing between diaphragm 69 and the adjacent face of the impeller.

Two outlets are provided from the cylindrical shell 43, the first, designated by numeral 71, communicating with diffusion vanes 58 for pumping impeller 52, and the second, designated by numeral 72, communicating with diffusion vanes 59 for mixing impeller 53. Desirably, outlet 72 is provided with a conduit 73 in which is mounted valve means 74, so that the intermediate component represented by dashed arrows, passing outwardly from the space surrounding mixing impeller 53 may be controllably recirculated to inlet 61, whereby this material will be introduced and dispersed with the mineral oil (second component), represented by the dash-dot arrows, entering inlet 60 to pass to the inlet eye of mixing impeller 51.

In operation, the apparatus of Figure II just described may take the place of mixers 16 and 20 as well as recycle pump 17 and bypass 39 of Figure I. With such an arrangement, mineral oil, represented by dash-dot arrows, is admitted through inlet 60, soap stock, represented by dotted arrows, is admitted through inlet 50, and finished grease, shown by solid line arrows, is discharged from outlet 71. Recirculation of finished grease into the soap stock to provide the intermediate component, as described above, takes place through valved conduit 73.

Though the process and apparatus of my invention have special utility in the manufacture of lime base greases, it is also adapted for use in connection with production of other commonly used greases, such as aluminum base grease and sodium base grease. In the manufacture of aluminum base greases the finished product grease as described in Figures I and II is preferably cooled quickly to about 120-180° F. and then allowed to stand, undisturbed, at a constant temperature for about 15 minutes to 24 hours until the desired aluminum base grease structure has formed.

The soap stock used in my process and apparatus may be made by any of the numerous methods well known in the art. Any of the various fats, fatty oils, fatty acids and the like ordinarily used as saponifiable materials in grease making may be employed, including oleic acid, stearic acid, hog fat, tallow, fish oils, saponifiable vegetable and animal oils, naphthenic acids, etc. Depending upon the type of grease desired and its use, any of the well known saponifying agents may be used, including calcium hydroxide, calcium oxide, magnesium, barium, strontium and lithium hydroxides or oxides, caustic soda, caustic potash, aluminum hydroxide, etc. Instead of preparing the soap, commercially manufactured dry soaps suitable for grease manufacture may be employed. When such procedure is followed, I usually insert the anhydrous soap in appropriate medium or carrier, such as a naphthenic base mineral oil of about 300 S. S. U. viscosity at 100°

F., or the like, and subject it to thorough mixing prior to dispersion in the recycled portion of the finished grease.

Naturally the type of soap stock employed will vary, according to well-known principles, with the kind of grease to be made and with the components of the grease.

Though it is not necessary that it be done, a small portion of the oil stock may be admixed with the soap before the soap stock is pumped into the system.

In the manufacture of lime base soap stocks it is usually desirable, and even necessary with most processes, to provide for the presence in the grease of a small percentage of water. The water content of lime base soap stocks varies in the range of 5-20% of the dry weight of the soap present. Such water is usually incorporated in the saponification step in the soap manufacture.

Of course, in operating my process as a fully continuous process, it is necessary to have a continuous supply of soap stock. Accordingly, an adequate number of soap kettles may be employed to supply the demand of the process for the soap stock. The charges to the soap kettles should be so timed that when the contents of one soap kettle has been used the soap from another kettle is available. Likewise, a continuous supply of oil must be available if the process is to be operated continuously.

The mineral oil stocks used may be those conventionally employed in grease manufacture, including mineral lubricating oils obtained from paraffinic, naphthenic and mixed base crudes, with or without various treatments usually given such oils. Oils obtained by polymerization, condensation, hydrogenation, etc., of hydrocarbons may also be used. The preferred viscosity of the mineral oil stock will usually vary according to the type of grease to be made. For aluminum soap grease, sodium soap grease and calcium soap grease preferred viscosity ranges, expressed in Saybolt Seconds Universal at 210° F., are respectively, 50-300, 40-300 and 40-200.

In my process, where the dispersion is obtained largely with the aid of the high speed mechanical disperser, it is nevertheless important that in the various mixing steps the soap stock, oil, intermediate component and recycled finished grease be maintained at proper temperatures. In the table are shown preferred temperatures at various stages of my process in the manufacture of lime, aluminum and sodium base greases.

Table

Temperature, Degrees Fahrenheit	Lime Base Greases	Aluminum Base Greases	Sodium Base Greases
60 Soap stock to 1st stage mixer.....	280-320	300-350	350-400
Recycle grease to 1st stage mixer.....	130-190	180-220	280-320
Heavy grease effluent from 1st stage mixer.....	137-196	186-226	283-324
Oil to 2nd stage mixer.....	117-184	174-213	276-315
Finished grease effluent from 2nd stage mixer.....	130-190	180-220	280-320

The proportions of soap stock and oil stock which will exist in the grease when it leaves the system will vary, of course, with the type of grease being made and its intended purpose. Soap content of greases varies from as low as 1% to as high as 60% and higher. The determination of what percentages of soap and oil stock to use to obtain the desired grease is one easily made by those normally skilled in the grease-making art. While our process and apparatus has special

utility in the manufacture of grease with a soap content of 10% or less, my invention is not limited to any specific range of soap percentages.

It is usually desirable to maintain the various elements, including soap stock vessels and oil supply vessels, pumps, mixers, etc. under super-atmospheric pressure of around 25 pounds per square inch. This is especially true in the manufacture of lime base greases, inasmuch as such greases normally contain considerable water 10 which should not be lost by evaporation.

I claim:

1. Continuous process of making grease, which comprises continuously intimately admixing proportional amounts of preformed soap stock and preformed grease to form an intermediate uniform dispersion, and continuously intimately admixing said uniform dispersion with a proportional amount of oil to form another uniform dispersion characterized by high stability and a reduced soap content as compared with the first mentioned dispersion.

2. In a continuous process of making grease wherein proportioned amounts of preformed soap stock and oil are subjected to high speed mixing to produce a dispersion of oil and soap stock, the improvement which comprises subjecting said soap stock in the presence of a proportioned amount of preformed grease to the action of a high speed mixer prior to forming a dispersion of said soap stock and oil, whereby said soap stock is conditioned for more efficient and stable dispersion in the oil.

3. In a continuous process of making grease of improved stability wherein proportioned amounts of preformed soap stock and oil are subjected to the action of a high speed mixer to produce a dispersion of soap stock and oil, the improvement which comprises subjecting said soap stock to the dispersing action of a high speed mixer in the presence of a proportioned amount of preformed grease prior to subjecting said soap stock to a further dispersing action in the presence of oil, said preformed grease being continuously recirculated grease resulting from the last mentioned dispersing action.

4. In a continuous process of making grease wherein proportioned amounts of preformed soap stock and oil are subjected to the action of a high speed mixer to produce a dispersion of soap stock 50 and oil, the improvement which comprises sub-

jecting preformed soap stock dispersed in pre-formed grease and a proportioned amount of oil to the dispersing action of a high speed mixer to produce a dispersion of oil and soap stock of improved stability.

5. Continuous process of making grease which comprises continuously passing to a high-speed disperser proportioned amounts of preformed soap stock and proportioned amounts of pre-formed grease, effecting an intimate dispersion of said soap stock and preformed grease in such first stage disperser to form an intermediate component, continuously passing such intermediate component and proportioned amounts of oil to a second high-speed disperser, effecting an intimate dispersion of said two components in said second disperser and recirculating proportioned amounts of the product of such second disperser to the first stage disperser as the finished grease component of the first stage disperser.

15 6. Continuous multistage process of grease making which comprises continuously passing proportioned amounts of preformed soap stock (component 1) and proportioned amounts of pre-formed grease continuously recirculated from a later stage in said multistage process (component 2) to a high speed disperser, continuously effecting an intimate dispersion of components 1 and 2 in said disperser by the shearing action of rapidly moving parts, continuously passing proportioned amounts of said dispersion (component 3) and oil (component 4) to a second such high-speed disperser and continuously effecting an intimate dispersion in said second disperser of proportioned amounts of components 3 and 4.

CHARLES RAY HETHERINGTON.
